VARIABLE SPEED GOVERNOR

Paul G. Kostenick, Scobey, Mont.

Application March 21, 1944, Serial No. 527,433

5 Claims. (Cl. 123—103)

This invention relates to a novel and improved variable speed governor for use in connection with gasoline or Diesel motors wherein the governor means proper is operated by and through the medium of oil pressure supplied by an appropriate lubricating pump connected with the crankcase or fuel transfer pump on Diesel motors, whichever the conditions may be, and my primary aim is to provide a new type of governor to replace the conventional mechanical ball-type centrifugal governor ordinarily used on present-day internal combustion engines and motors.

Briefly, the improved governor construction is characterized by an oil pressure actuated diaphragm embodied in a special oil cylinder or receptacle therefor, this being a spring-retumed type having direct mechanical connection with the engine throttle, oil being delivered to said cylinder by a conduit leading from the source of oil supply and said conduit including a circulatory pump.

More specifically, the diaphragm-equipped oil cylinder has a return line connected thereto, the return line also connecting with the crankcase, and there being hand-regulated valve means associated with the return line adjacent the cylinder for thus enabling the user to predetermine and obtain the desired nicety of regulating control.

In carrying out the preferred embodiment of the invention I have devised a unique structural arrangement characterized by a minimum of parts thus insuring efficiency in simplicity, the parts chosen being so coordinated to cooperate in insuring full throttle control over the full speed range of an engine, whereby to provide for more effective and selective speed control results.

Other features and advantages will become more readily apparent from the following description and the accompanying illustrative drawings.

In the drawings, wherein like numerals are employed to designate like parts throughout the same:

Figure 1 is a side elevational view of a conventional internal combustion engine, with certain parts omitted for clearness of illustration, this showing the variable speed governor as constructed in accordance with the principles of the instant invention and illustrating its preferred association with conventional parts and including, further, auxiliary devices acting as components of the governor structure as a unitary arrangement.

Figure 2 is a view partly in section, and partly

in elevation, bringing out the construction and arrangement of individual details to a degree of greater clarity and sufficiently, it is believed, to reveal all essential parts of the governor and its associated adjuncts.

Referring now to the drawings by distinguishing reference numerals it will be observed that the numeral 3 designates the aforementioned receptacle or cylinder. This is of appropriate material and dimensions and suitably mounted on the cylinder block as brought out in Figure 1. At the right hand flanged end 4 I provide a suitable closure plate 5 whose outer marginal portion is bolted or otherwise secured to the flange 4. The central portion of the plate is somewhat concaved and provided with a bearing having a suitable packing gland 6 through which a control rod 7 reciprocates. This rod is secured at its inner end to a concave-convex diaphragm 8. More specifically, the rod 7 is bolted or otherwise connected with the central portion of the diaphragm and a coiled spring 9 surrounds the rod, bears at one end against the bearing 10 and at its opposite end against the diaphragm connection. The outer perimeter of marginal edge of the diaphragm is clamped between the flange 4 and the closure plate 5. This spacing of parts 5 and 8 provides a chamber between the two.

While considering this end of the governor structure it will be noted in Figure 2 that the conventional throttle 11 is actuated by a crank arm 12 and intervening link 13, the latter being pivotally connected to the crank arm and likewise pivotally connected to the push-pull control rod 7. Oil is introduced into the left-hand end of the cylinder 3 by way of an inlet or feed neck 14. The oil delivery line or conduit 15 is connected, suitably, to this neck 14. The intake end of the line 15, as indicated at the point 16, is connected to the crankcase A (in case of a Diesel motor hook-up this pipe end 16 would be connected to the fuel oil tank not shown). An appropriately driven circulating pump 17 is mounted in the conduit to pick-up the oil from the crank case A and to deliver it into the cylinder 3 by way of the line 15. A Y-shaped valve casing 18 is embodied in the conduit and is provided with a ball-check valve 19. There is also a branch pipe 20 which leads off from this coupling or connection 15 to deliver lubricating oil to the engine and other parts thereof, (or as in the case of a Diesel engine, fuel oil to the fuel injection system).

A substantially T-shaped valve fitting or casing 21 is mounted atop the central portion of the cylinder 3, having communication therewith

through the branch indicated. A return line 22 leads from this valve casing 21 back to the crankcase A to serve a purpose to be hereinafter explained. A needle or equivalent valve 23 contacts with the seat 24, this valve being on an adjusting rod 25 operating through an adapter branch 26. A coil spring is located in this tubular branch 26 and surrounds the rod and exerts pressure on the shoulder, as indicated, to assist in opening or unseating said valve 23. The rod 25 is screw-threaded as at 27 and operates through a screw-threaded sleeve 28 on an attaching bracket 29, this being fixedly mounted on the dash as shown in Figure 1. For purposes of adjusting the screw-threads the rod is provided with an appropriate hand-grip 30. A branch pipe 31, which serves as a by-pass, affords communicating connection between the oil return line 22 and the chamber which is formed in the cylinder at a point between the diaphragm 8 and closing plate 5. Oil which accumulates in this chamber acts as a lubricant for the rod 7 and bearing 10 to promote movements of operation of the parts and such oil can be bled from the chamber by way of the plug screw 32. A similar drain plug 33 is provided in the bottom of the cylinder 3, this also for purposes of bleeding the system.

An operating element 34 is connected to the rod 7 and is, in turn, provided with a flexible depending portion 35 which connects with a control wire 36 which is, in turn, operable through a flexible shaft 37, said wire being pushed back and forth by a knob or finger-grip 38. This flexible shaft or wire 36 provides an auxiliary hand control for the governor control rod 7.

Explaining the operation of the invention, it can be seen that when the lubricating pump 17 is in operation, oil is drawn up from the crankcase A and forced up and by the ball check valve 19, then on up through the pipe 15 and into the cylinder 3 by way of the inlet 14. The oil in this cylinder exerts pressure against the diaphragm 8 forcing it against the spring 9 and causing the throttle 11 to close by means of the operating or connecting rod 7, thus causing the engine to slow down. When higher speed is desired, the valve 23 is opened, this by means of the control rod 25, which relieves oil pressure in the cylinder against the diaphragm, thus allowing the spring 9 to force the diaphragm back and to open the throttle 11. The overflow of oil escaping through this valve 23 is returned to the crankcase (or to the fuel tank in the case of a Diesel motor) by means of the return line 22. It can be seen that by properly setting the valve 23, that is, in a predetermined position, an equally predetermined pressure will be maintained in said cylinder 3 acting on the diaphragm and, therefore, holding the throttle in a fixed or one position. When, however, the motor load happens to vary, causing it to slow down, the oil pump 17 will obviously decrease its output and lower the pressure in the cylinder 3, which causes the throttle to open. If the load becomes lighter, the engine would tend to speed up and cause the pump to increase the output and also increase the pressure in the cylinder, exerting pressure on the diaphragm, which would decrease the throttle opening by way of the control rod 7. The obvious purpose of the bracket or element 34 is that of an auxiliary control to manipulate the throttle when the governor is not operating as in the case when the engine is to be started. As before stated, the auxiliary

control element 34 is under the influence and action of the flexible shaft 36 and its operating finger-piece 38.

It can be seen that the valve 23 acts as a means of variable speed control due to the fact that the oil pressure in cylinder 3 is controlled by manual adjustment of this valve which, in turn, determines the actions of the diaphragm 8.

The purpose of the check valve 19 is to prevent oil from draining out of the governor control mechanism, whereby to keep said mechanism in readiness, at all times for sensitive functioning.

It is thought that persons skilled in the art to which the invention relates will be able to obtain a clear understanding of the invention after considering the description in connection with the drawings. Therefore, a more lengthy description is regarded as unnecessary.

Minor changes in the shape, size and arrangement of details coming within the field of invention claimed may be resorted to in actual practice, if desired.

Having described the invention, what is claimed as new is:

- 25 1. In a structural assemblage of the class described, in combination, an engine, said engine including a crankcase laden with oil, a cylinder, a diaphragm in said cylinder, a throttle, an operating connection between the diaphragm and throttle, a conduit connected at one end with said cylinder and at its opposite end with said crankcase, and a pressure circulating pump in said conduit, together with a check valve in said conduit above the pump and below the cylinder.
- 30 2. In a structural assemblage of the class described, in combination, an engine, said engine including a crankcase laden with oil, a cylinder, a diaphragm in said cylinder, a throttle, an operating connection between the diaphragm and throttle, a conduit connected at one end with said cylinder and at its opposite end with said crankcase, and a pressure circulating pump in said conduit, together with a check valve in said conduit above the pump and below the cylinder, and a branch pipe-line connected with said conduit below the check valve and above the pump for delivering oil to the engine and associated parts thereof.
- 35 45 3. In a structural assemblage of the class described, in combination, an engine having a throttle, a crankcase, a pressure circulating pump, a connection between the pump and crankcase, a variable speed control governor embodying a cylinder, a diaphragm mounted in said cylinder, a mechanical operating connection between the diaphragm and throttle, a valved conduit between the cylinder and pump, and a valved return line between the cylinder and the crankcase, together with a by-pass pipe between the return line and diaphragm equipped end of said cylinder.
- 50 55 60 70 4. A variable oil pressure type speed governor for engines and motors comprising a cylinder having an oil intake at one end, the opposite end being provided with a closure plate having a central bearing, an oil pressure operated diaphragm in the cylinder between the closure plate and adjacent end of the cylinder, a reciprocatory control rod slidable in said bearing, the inner end of said rod being secured to the central portion of said diaphragm, a coiled spring surrounding the rod between the diaphragm and interior of said closure plate, an oil return pipe, a valved connection between said return pipe and cylinder, and a branch pipe connection between said return

pipe and the chamber formed between the diaphragm and closure plate.

5. A variable oil pressure type speed governor for engines and motors comprising a cylinder having an oil intake at one end, the opposite end being provided with a closure plate having a central bearing, an oil pressure actuated diaphragm in the cylinder between the closure plate and adjacent end of the cylinder, a reciprocatory control rod slideable in said bearing, the inner end of said rod being secured to the central portion of said diaphragm, a coiled spring surrounding the

5

10

rod between the diaphragm and interior of said closure plate, an oil return pipe, a valved connection between said return pipe and cylinder, and a branch pipe connection between said return pipe and the chamber formed between the diaphragm and closure plate, a flexible shaft, and an operating connection between the flexible shaft and said reciprocatory throttle control rod, the latter parts constituting an auxiliary manual control for said throttle rod.

PAUL G. KOSTENICK.
